UNITED STATES PATENT OFFICE.

CHARLES F. PYM, OF ESSEX, ONTARIO, CANADA, ASSIGNOR OF ONE-HALE TO KRENTLER-BROTHERS COMPANY, OF DETROIT, MICHIGAN, A CORPORATION OF MICHIGAN.

LASTING-MACHINE.

No. 907,524.

Specification of Letters Patent.

Patented Dec. 22, 1908.

Application filed August 1, 1906. Serial No. 328,691.

To all whom it may concern:

Be it known that I, CHARLES F. PYM, a citizen of Canada, residing at Essex, in the Province of Ontario, Canada, have invented an Improvement in Lasting-Machines, of which the following description, in connection with the accompanying drawings, is a specification, like letters on the drawings representing like parts.

10 My invention is an improvement in lasting jacks of the kind shown in my Patent No. 755,544 dated March 22, 1904.

15 My present invention resides in providing a more positive feeding movement in connection with more positive control on the part of the operator, so that he can position the shoe with greater certainty and secure better crimping results, which is of particular advantage at the heel.

20 The constructional details and various advantages of my invention will be pointed out more at length in the course of the following description, reference being had to the accompanying drawings, in which I have 25 shown a preferred embodiment of my invention.

In the drawings: Figure 1 is a perspective view of a lasting machine provided with my improvements; Figs. 2 and 3 are fragmentary details in top plan and side elevation of the flattener which operates with the wiper of the machine and with the lasting jack for permitting the shoe to be swung around and handled readily; Fig. 4 is a central longitudinal section view of the lower portion of the jack support; Fig. 5 is a view in front elevation thereof; and Fig. 6 is a view in front elevation, the lower part being in section, showing the upper part of the jack and illustrating its movement in dotted lines.

40 It will be understood that my improvements may be used with any usual lasting machine, the form herein shown comprising a head 1 on a suitable pedestal 2 provided with tack driving mechanism, consisting of a nozzle 3, raceway 4, driver head 5 operated by an arm 6 and eccentric 6^a, the tacks being delivered from a hopper 7 operated by a stirrer rod 8 and wormwheel 9 and worm 10 from a shaft 11. A wiper 12 is operated by an eccentric 13 on a tack driver shaft 14.

45 In my patent I have shown the shoe and last as supported on a more or less complicated head support and arrangement, which 50 it is one purpose of my present invention to

do away with. Accordingly I have provided a simple jack spindle 15 having a usual pin 16 for entering the thimble or socket hole in the heel end of the last, said spindle being pivotally mounted at 17 in the bifurcated upper end of a coupling 18 provided with an ear 19 at its lower end fitting tightly in a slot 20 provided therefor between the opposite ears 21, 22, of a sliding stem 23 supported on a spring 24 in a sleeve 25 pivoted at 26 to a rocker arm 27 fast on a shaft 28 to the outer end of which is secured a crank 29 operated by a rigid arm 30 from the driving shaft 14 by any suitable means, as by an eccentric pin 31. The result is that the upward pressure of the jack is automatic and in timed relation to the tack driving as distinguished from irregular and not in timed relation as in my previous jack patent, so that the jack runs in perfect time with the tack driver, enabling 75 the latter to drive all the tacks correctly. The movement of the jack takes place every time the workman drives a tack and the jack holds the shoe strongly up against the wiper and the nozzle at the moment the tack is 80 driven, and then when the tack has been driven, the jack lowers so that the shoe is free to feed. Thus the workman merely has to guide the shoe, the machine doing the rest. The stem 23 carries a ratchet 32 engaged by a dog 33 automatically released by an arm 34 projecting forward from a bracket 35. The sleeve 25 is yieldingly supported in angular position by an arm 36, link 37 and spring 38. The ear 19 of the coupling 18 is 85 not loosely pivoted to its support 23 as in my patent, but is held positively in fixed adjustment by any suitable means. I have shown a clamp comprising a threaded bolt 39 engaged by a threaded cap 40 operated by a 90 handle 41 so that the angle of the spindle 15 with relation to the nozzle 3 and wiper 12 may be set according to the requirements of the individual case and yet leave the spindle free to oscillate in a plane transverse to the 100 movement of said wiper, as indicated in dotted lines in Fig. 6. By this means the angle of the shoe in the machine is determined, for lasting the heel on a round corner or a square corner, for example. This gives also steadiness and certainty of position with relation 105 to the wiper and enables the operator to manipulate the shoe readily notwithstanding that it is mounted simply on a single jack spindle and pin. Coöoperating with this fea-

110

ture in giving steadiness and aiding in holding the shoe in proper position as it is turned and shifted about, and also aiding in flattening the crimped leather, is a nozzle foot or flattener block 42, clamped immovably at the lower end of the nozzle 3 by any suitable means, as by a screw 43. The crimper 12 is bifurcated to straddle this flattener 42, thereby coöoperating therewith to wipe down and 10 crimp the upper. Not only does this flattener 42 aid in maintaining the shoe and last in position, but as the tack is driven while the shoe is being forced up by the spring 24 strongly against the nozzle and wiper, all the 15 tacks are thereby driven into the shoe a uniform depth, and it helps to make a flat seat and to prevent the upper from being trapped or caught between the nozzle and the wiper when the upper is short at the seat, as frequently happens. Undersuch circumstances 20 it has been common heretofore for the leather to catch between the nozzle and wiper and either tear the leather or bend or break the nozzle.

25 I can best describe the operation of my invention in connection with lasting heel seats. When the jack moves down away from the nozzle and wiper, due to the upward movement of the crank 29, which lowers the rocker arm 27 and thereby depresses the jack, the operator feeds the shoe forward by swinging the spindle slightly on its pivot 17, the jack immediately rises and forces the shoe against the nozzle-footrest or flattener 42 with a 30 strong force, operating to flatten the seat and crowd and press the leather down strongly against the last on which it is being lasted. This helps the wiper with its work, preventing the formation of a ridge in the leather between the edge of the shoe and last and the 35 nozzle. The flattener 42 spreads or distributes the pressure of the jack and makes the work much more even. It coöperates with the constant up-and-down motion of the jack to hammer the heel seat, as well as smooth and iron the same and prevent the trapping of the leather, already mentioned, and it gives a broad bearing on which to swing and move the shoe, tending to help maintain the 40 shoe in proper position in connection with the spindle support 15.

If the operator desires to move the shoe temporarily nearer or farther from the wiper and tack driver, he can do so simply by 45 swinging the entire jack in opposition to the spring-held arm 36, without changing the clamp 40. The latter is adjusted to suit different sizes of shoes and styles of work, and is for the purpose of giving steadiness of movement and aiding the operator in directing the

movements of the shoe. The jack is always in its highest position or point of travel when the tack is driven, at which time the shoe is held firmly against the nozzle and flattener, the result being that the tacks are driven 65 into the shoe evenly and are properly and rapidly clenched.

Having described my invention, what I claim as new and desire to secure by Letters Patent is,

70 1. In a lasting machine, a tack driver, a reciprocating wiper, and lasting jack, and operating means therefor operated in timed relation to the tack driving, said lasting jack and its operating means pressing the last and 75 shoe vertically up at the time of tack-driving against the wiper and tack driver in opposition to their downward pressure on the bottom of the last, the aforesaid mechanism including means for hammering vertically the 80 crimped leather down upon the bottom of the last as it is being laid by the wiping movement and pressure of said wiper.

85 2. In a lasting machine, tack-driving mechanism and its operating means, a wiper, operating means therefor operating in timed relation to the tack-driving mechanism, to engage the shoe when a tack is driven, a jack for holding the shoe with relation to said tack-driving mechanism and wiper, and 90 automatic means for forcing said jack and its shoe strongly against said wiper each time a tack is driven.

95 3. In a lasting machine, tacking mechanism including a nozzle, lasting mechanism including a lasting jack, means for imparting an up-and-down feeding movement to said jack with relation to said nozzle, and a laterally extending flattener block fast on the lower end of said nozzle for coöoperating with 100 said lasting jack in flattening the leather and steadyng the work.

105 4. In a lasting machine, a tack driver provided with a nozzle, a reciprocating wiper operating in line with said nozzle, said wiper having a bifurcated crimping end, and a narrow flattener block extending rearwardly over the edge of the last in line with said wiper to rest on the shoe between the projecting ends of the wiper as the latter reciprocate, for preventing injury to the leather and aiding in flattening the crimps of the leather and steadyng the work.

110 In testimony whereof, I have signed my name to this specification, in the presence of 115 two subscribing witnesses.
